(57) **CLAIM**

We claim the ornamental design for a lamp for projector, as shown.

DESCRIPTION

FIG. 1 is a front, top and left side perspective view of a lamp for projector showing our new design;

FIG. 2 is a front elevational view thereof;

FIG. 3 is a reduced rear elevational view thereof;

FIG. 4 is a top plan view thereof;

FIG. 5 is a reduced bottom plan view thereof;

FIG. 6 is a left side elevational view thereof; and,

FIG. 7 is a reduced right side elevational view thereof.

The broken lines showing portions of a lamp for projector are included for the purpose of illustrating environmental structure and form no part of the claimed design.
